UNITED STATES PATENT OFFICE.

GEORGE GULICKSON, OF CHICAGO, ILLINOIS.

GRATE AND FURNACE FOR STEAM-BOILERS.

SPECIFICATION forming part of Letters Patent No. 380,719, dated April 10, 1888.

Application filed July 26, 1886. Serial No. 209,129. (No model.)

To all whom it may concern:

Be it known that I, GEORGE GULICKSON, a citizen of the United States, residing in Chicago, in the county of Cook and State of Illinois, have invented a new and useful Improvement in Grates and Furnaces for Steam-Boilers, of which the following is a specification.

My invention relates to furnaces for steam-boilers.

- 10 In the accompanying drawings, which form a part of this specification, and in which similar letters of reference indicate like parts, Figure 1 is a cross sectional view of a furnace embodying my invention. Fig. 2 is a horizontal sectional view taken on line 2 2 of Fig. 1. Fig. 3 is a longitudinal sectional view taken on line 3 3 of Fig. 1. Fig. 4 is an enlarged detail view showing the bearing of the rocker-bar. Fig. 5 is an enlarged longitudinal vertical section showing the sliding dump-plate. Fig. 6 is a front view of a portion of the furnace-front. Figs. 7, 8, and 9 are enlarged detail views of one of the rocker-bars and the ends of the grate bars. Fig. 10 is a 25 detail sectional view showing one of the side grate-bars for locking the movable grate-bars in place. It is taken on line 10 of Fig. 2. Fig. 11 is a front view showing the sliding dump-plate and its supports. Fig. 12 is an enlarged 30 detail sectional view showing the mechanism for operating the rocker-bars. Fig. 13 is a plan view showing the lever-socket. Fig. 14 is a perspective view showing the end of the operating-lever. Fig. 15 is a section on line 35 15 15 of Fig. 1. Fig. 16 is a side elevation of one of the rocker-bars, and Figs. 17 and 18 are views illustrating a slight modification specially adapted to the application of the invention to old furnaces. Fig. 19 is a vertical 40 cross-section taken through the center of the arched tile. Fig. 20 is a vertical cross-section through the operating-lever, the handle, and registering-guard, showing the socket in which the removable handle fits.

- 45 In said drawings, A represents the furnace-walls; B, the boiler; C C, the cast-iron side stands or supports at the front of the boiler, and C' the middle stand or support.

- 50 D D are the rocker-bars; E E, the side frame-pieces or supports upon which the rocker-bars are mounted.

F F F are the shaking grate-bars, mounted upon the rocker-bars D D.

G G are the stationary side or grate bars, which serve to lock the movable or shaking 55 grate-bars in place.

The side supports or bars, E E, may be embedded in the masonry and supported thereby. These side frame-pieces, E E, are furnished with circular recesses e e, furnished 60 with rounded ledges or projections e' e' for the ends of the rocker-bars D D. The under or bearing surface of the rocker-bar ends d d is preferably about flat, as illustrated in Fig. 4, and rests directly upon the curved or rounded 65 surface of the ledge e' on the frame E, so that the rocker-bar has a rolling or rocking motion upon its bearing. This materially diminishes friction and facilitates the operation of the 70 grates.

Heretofore the rocker-bars have usually had a pivotal or turning motion on their bearing, as contradistinguished from a rocking or rolling motion, and as these bearings are peculiarly liable to be obstructed by ashes and cinders and the heat of the furnace difficulty has been frequently experienced in their operation. To properly center the rocker-bar upon its 75 bearings and keep it in place, I furnish the bearing ends d of the rocker-bar with a notch 80 or recess, d', in which fits a corresponding projection, e', on the bearing e', and the rocker end d is also furnished with overlapping projections d' d' at each edge. To compensate for the expansion and contraction of the grate-bars in length and the consequent movement 85 of the rocker-bars, the notch or recess d' is made somewhat wider than the corresponding projection e'.

The rocker-bars D are each furnished with 90 two cam-wings or curved projections, d³ and d⁴, upon which the shaking grate-bars F rest. Each of the grate-bars F is provided at each end with an open eye or curved recess, f, which fits upon and corresponds in shape to the bearing wings or projections d³ or d⁴ on the rocker-bars D D. The bearing-recess f on each alternate grate-bar fits at each end upon the left-hand wings or cams, d³, on the two rocker-bars, and the two rocker-bars are connected together, 100 so that they move in unison and operate to move or raise both ends of the grate-bar at the

same time. The other half of the grate-bars, or their bearing recesses or grooves f , fit upon the two right-hand wings or projections, d^4 , of the rocker-bars D D. In this way each alternate rocker-bar will be raised while the others are depressed and depressed while the others are raised. The bearing ends d of the rocker-bars D are offset, as shown in Fig. 16, so that the under bearing-surface of the same, which rests upon the ledge e' , will be on a level with the wings d^3 d^4 , upon which the grate-bars rest. In this way the grate-bars will be given little endwise movement by the limited rocking motion of the rocker-bar, and the motion of the grate-bars will be chiefly up and down. The grate-bars are each alternately cut away at each end at d^3 d^4 , so that each grate-bar at each end will have a bearing upon only one of the wings d^3 d^4 . The grooves or recesses f in the grate-bars are of a hook shape and somewhat encircle the bearing wings or cams d^3 d^4 on the rockers D, so that the grate-bars cannot be placed upon their rocker-bars except by sliding or lateral movement lengthwise of the rocker-bar, and so that the grate-bars will be securely held and fixed upon the rocker-bars at each end. The bearing wings or cams d^3 d^4 do not extend the full length of the rocker-bar, but are cut away at each end, as indicated in Figs. 8, 9, and 16, so that the grate-bars may be slipped over the ends of these wings or projections. In Fig. 9 the front grate-bar shown is illustrated as being lowered into position to slip over the end of the rocker-bar wings d^3 d^4 . A stationary or locking grate-bar, G, fits in at each side of the grate and covers this portion of the rocker-bar D at each end where the bearing wings or cams d^3 d^4 are cut away. These stationary grate-bars are provided with dovetail projections g , which fit in corresponding dovetail projections, g' , cut in the frame-bars E E, whereby the stationary grate-bars are supported and held in place. The projections g upon the bars G need be only dovetailed at one end of said bars, the projection g' at the other end being plain, as indicated at Figs. 2 and 10. The stationary grate-bars G serve to prevent any lateral movement of the grate-bars and to hold them in place.

The rocker-bars D D are provided with arms D', the lower ends of which arms are connected together by a connecting-bar, D'', to which said arms are pivoted. Owing to the peculiar form of the eyes or bearing-recesses f in the grate-bars and the bearing wings or cams d^3 d^4 on the rocker bars D, and the fact that each grate-bar has such eye or bearing-recess at each end, the grate-bars themselves would serve to connect the rocker-bars together and cause them to move in unison; but it is desirable to provide each rocker-bar with an operating-arm and connect the two together by a connecting-bar, as shown and before described.

The grate is operated through a connecting-rod, H, by a lever, H', which is pivoted to a

bracket, h, secured to the front of the furnace. This lever is provided with a socket, h', at its outer or upper end for the handle H''. Rigidly secured to the connecting-rod H is a slotted casting or block, H³, and to this casting the lever H is pivotally connected. The handle H'' is provided with a projection or projections, h², which fit in corresponding slots or recesses, h³, in the slotted casting or block H³, so that the handle H'' can only be inserted into its socket when said socket registers centrally with these little slots or recesses h³ in the block H³—that is to say, when the rocker-bars occupy their central position and the upper surfaces of the grate-bars are all level with each other.

By referring to Figs. 12, 13, and 20 it will be readily seen that the registering guard or block H³, which is secured rigidly to the reciprocating rod H, will prevent the insertion of the handle H'' in its socket h' in the lever H', except when said lever is so swung or turned on its pivot as to bring the end or socket h' in the end of said lever directly under the notches or recesses h³, cut in the registering block or guard H³, so that the pin or projection h² on the sides of the handle may pass through said notches or recesses h³, and thus permit the end of the handle to enter its socket. The overhanging flanges of the guard-block H³ on each side of its central slot, in which the handle H'' and lever H' play back and forth, likewise prevent the removal of the handle from the socket of the lever, except when the lever is so turned on its pivot that the pin h² on the handle will register with the notches or recesses h³ in the guard-block H³—that is to say, when the lever H' is in such position as to leave the grate-bars all level. By this means the operating-handle only can be removed from its socket when the grate-bars are all level with each other. After shaking the grate, if the surface of the grate is not level and the alternate grate-bars project above the others they are liable to be greatly burned and injured by the heat. I therefore greatly increase the durability of the grate by providing means for always insuring that the surface of the grate is left level after each shaking operation.

J J are my sliding dump-plates at the front end of the grate-bars. They are mounted on suitable guideways, c, on the side and middle stands, C C', and slide horizontally beneath the fixed plate J'. J'' is the pull-rod by which these sliding dump-plates are operated. Each of the rods J'' is furnished with a projection, j, which passes through a slotted or notched hole, j', in the front plate of the furnace, so that the sliding dump-plate cannot be moved until its operating-rod is turned in a particular position.

K is the bridge-wall. It is made hollow or provided with a central passage, K', communicating at k with the space beneath the grate and surmounted by a fire-tile, L, furnished with perforations L', which communicate with

the fire-space. The central hollow tile M also communicates fresh air from the hollow bridge-wall, and thence through the central arched tile, N and the perforations n to the fire-space. By 5 this means fresh air is led from under the grate to the products of combustion through the perforations in the tile L and the central arched tile N as said products pass over the bridge-wall, thereby materially facilitating combustion and 10 increasing the heat. The two fire-tiles M' M' on each side of the central tile M, as well as the two arch-tiles N N on each side of the middle arched tile N, I make solid. The arch-tiles N N are made in about the form shown in Fig. 15 1, and are provided with a notch, n', at each outer end to fit upon a recess in the masonry, and another notch, n'', at their lower end to fit upon the vertical tile M.

As shown in Figs. 3, 15, and 19, the fresh 20 air passes from the ash-pit or space below the grate through the opening k in the bridge-wall K into the hollow space K', and it thence passes in part through the perforations L' in the tile L and unites with the products of combustion as the same pass over the bridge-wall. Part of the fresh air passes from the 25 hollow space K' up through the hollow central tile M into the hollow arch-tile N, and thence down through the perforations n in said 30 arch-tile into the fire-space, where this part of the fresh air also unites with the products of combustion as the same pass over the bridge-wall. By this means the supply of 35 fresh air is admitted from both above and below and the combustion made more perfect.

In Figs. 17 and 18 I have shown a form of my invention specially applicable to furnaces already erected. In this case the ends of the 40 frame side bars, E E, rest upon the ledges upon which the ends of the old grate bars rested. The grate-bars are cut a little shorter, and the space which would otherwise be left at their ends is filled by angle-plates x x. The block or casting H³ is made integral with the 45 connecting-bar D², and the arm D' on the rocker-bar is bent and provided with the socket for the handle H², which projects out through the door. In this way I save the necessity of drilling or cutting any holes through the center stand or front of the furnace. In this 50 modification, as shown in Figs. 17 and 18, the operating-lever H', as well as the connecting-rod H, is dispensed with, or, rather, the operating-lever is made integral with the 55 operating-arm D' of the rocker-bar, the bearings d e' of the rocker-bar thus becoming the fulcrum or pivot of the operating-lever, around which the bent arm D' and the handle H², fitted in the socket h' in the end of said bent arm, 60 swing as a center. The registering guard or block H³, secured on the extended end of the connecting-bar D², reciprocates back and forth, while the bent end of the operating-arm D' and the handle-socket h' therein move in the arc 65 of a circle around the bearing of the rocker-bar D as a center, so that it is obvious that the lever H² can only be removed or inserted in

its socket in the end of the bent arm D' when said bent arm is in a certain position—that is to say, when it or the handle-socket therein 70 registers with the notches or recesses h³ in the guard-block H³ on the end of the extended bar D². The guard-block H³ and the notches or recesses h³ therein, as well as the handle H² and its pin or projection h², used in this modified 75 construction, are precisely the same in construction, function, and operation as before described in relation to the other figures.

The frame-bars E E, I prefer to support at the front end on a suitable projection, p, cast 80 upon the side front stands, C, as indicated in Fig. 3, and at the rear end upon a suitable lug, p', embedded in the masonry, the frame-bars E being furnished with suitable notches to engage the same, as indicated in said Fig. 3. 85 The locking projection g² on the bar G is furnished with a depending notch or projection, g³, that fits over the side of the frame-bar E, and the bar G is also furnished with a projection, g⁴, to fit under the bar E, to better lock 90 the parts in place.

I claim—

1. The combination, with rocker-bars D D, having bearing wings or cams d³ d⁴, of grate-bars F, having bearing eyes or grooves f at 95 each end, the bearing eyes or grooves in the alternate grate-bars fitting on the opposite wings or cams on said rocker-bars, substantially as specified.

2. The combination of grate-bars F F with 100 rocker-bars D D and frame-pieces or supports E E, furnished with raised ledges e', said rocker-bars having a rocking or rolling bearing on the raised ledges e' of said frame-pieces or supports, substantially as specified. 105

3. The combination, with grate-bars provided with bearing eyes or grooves at both ends of said bars, of a pair of rocker-bars provided with bearing wings, said bearing eyes or grooves partially encircling said bearing-wings, substantially as shown and described, whereby the grate-bars are held in place and adapted to be put in place or removed only over the end of said bearing-wings, substantially as specified. 110 115

4. The combination, with shaking grate-bars F F, of rocker-bars D D, upon which said grate-bars are mounted, a movable operating-lever connected with said rocker-bars and provided with a handle-socket, a handle adapted to be 120 inserted in said socket, and a movable slotted registering guard plate or block provided with a recess through which said handle may be inserted into the socket of said operating-lever when the rocker-bars occupy their normal position, said slotted guard plate or block being attached to the movable connecting-rod connecting the operating-lever with the rocker-bars, and said handle being provided with a projection or enlargement to prevent its insertion or removal except when the socket of the operating-lever registers with the guard-plate and the rocker-bars are thus left in their normal position, substantially as specified. 125 130

5. In a furnace, the combination, with the grate, of bridge-wall K, having a central passage, K', communicating with the space below the grate, fire-tile L, surmounting said bridge-wall, provided with perforations L', central hollow tile M, and central hollow arch-tile N, communicating with said tile M and having perforations n, leading into the fire-space, said central hollow tile M communicating with said hollow bridge-wall, substantially as specified.

6. In a furnace, the combination of the grate, bridge-wall K, and arch-tile N N N with the central vertical supporting-tile M M M, said tile N N N having notches or offsets n' n' at their ends, substantially as specified.

7. The combination of the grate-bars F, having open bearing eyes or grooves f and cut-away portion d³ d⁴ at its ends, and the rocker-bars D D, having bearings d³ d⁴, said bearing-wings being cut away at the end to permit the insertion of the grate-bars, substantially as specified.

8. The combination of the grate-bars F, having open bearing eyes or grooves f and cut-away portion d³ d⁴ at its ends, and the rocker-bars D D, having bearing-wings d³ d⁴, said bearing-wings being cut away at the end to permit the insertion of the grate-bars, said rocker-bars having a rocking or rolling anti-friction bearing upon their pivots or supports, substantially as specified.

9. The combination, with grate-bars, of rocker-bars D D and frame-pieces or supports E E, furnished with curved bearing-ledges e' e', said rocker-bars D D being furnished with flat bearing ends d d, resting upon said ledges e' e', whereby said rocker-bars are given a rolling motion on said curved bearing-ledges, substantially as specified.

10. The combination, with grate-bars, of rocker-bars D D and frame-pieces or supports E E, furnished with bearing-ledges e' e', said rocker-bars D D being furnished with flat bearing ends d d, resting upon said ledges e' e', said ledges being provided with projections e² e², and said bearing ends d d being provided with corresponding notches, d' d', substantially as specified.

11. The combination, with grate-bars F F, having bearing-grooves f, of rocker-bars D D, having each a pair of bearing cams or wings, d³ d⁴, for said grate-bars, and supports or frame-pieces E E, having bearing-ledges e' e', said rocker-bars D D having offset bearing ends

d d, to bring the center of motion on about a level with said cams or wings d³ d⁴, said bearing cams or wings d³ d⁴ on each rocker-bar D engaging each the eyes of alternate grate-bars, substantially as specified.

12. The combination, with grate-bars F F, having bearing-grooves f, of rocker-bars D D, having bearing cams or wings d³ d⁴ for said grate-bars, supports or frame-pieces E E, having bearing-ledges e' e', said rocker-bars D D having offset bearing ends d d, to bring the center of motion on or about a level with said cams or wings d³ d⁴, operating-arms D' D', connecting-bar D², connecting-rod H, lever H', furnished with a handle-socket, handle H², having projections h², and slotted block H³, having notch h³, substantially as specified.

13. The combination, with shaking grate-bars, of rocker-bars D, operating-arms D', connecting-bar D², connecting-rod H, lever H', having handle-socket h', handle H², having projection h², and block H³, having notch h³, substantially as specified.

14. The combination, with side frame-pieces or supports, E E, of rocker-bars D D, having wings or cams d³ d⁴, grate-bars F F, having bearing-grooves f, partially encircling said wings or cams d³ d⁴, said bearing-grooves f being of a hook shape, and said wings or cams d³ d⁴ being enlarged to fit within the hollow of such hook-shaped bearing-grooves, and thus adapted to be inserted in place only over the ends of said cams or wings, and removable stationary locking side grate-bars, G, secured to one of said pieces E, substantially as specified.

15. The combination, with side frame-pieces or supports, E E, of rocker-bars D D, having wings or cams d³ d⁴, grate-bars F F, having bearing-grooves f, partially encircling said wings or cams d³ d⁴, said bearing-grooves f being of a hook shape, and said wings or cams d³ d⁴ being enlarged to fit within the hollow of such hook-shaped bearing-grooves, and thus adapted to be inserted in place only over the ends of said cams or wings, and removable stationary locking side grate-bars, G G, said bars G G and frame-pieces E E being furnished with interlocking grooves and projections, whereby the bars G G are supported from and secured to said frame-pieces, substantially as specified.

GEORGE GULICKSON.
